UNITED STATES PATENT OFFICE

98,998

DESIGN FOR A SHOE OR SIMILAR ARTICLE

Marcel M. Braun, Chicago, Ill.

Application February 17, 1936, Serial No. 61,207

Term of patent 3½ years

To all whom it may concern:

Be it known that I, Marcel M. Braun, a citizen of the United States, residing in Chicago, in Cook County, in the State of Illinois, have invented a new, original, and ornamental Design for a Shoe or Similar Article, of which the following is a specification, reference being had to the accompanying drawing, forming part thereof.

I claim:

The ornamental design for a shoe or similar article, substantially as shown.

MARCEL M. BRAUN.
